UNITED STATES PATENT OFFICE.

CHARLES E. CHAPMAN, OF FORT EDWARD, NEW YORK, ASSIGNOR, BY MESNE ASSIGNMENTS, OF ONE-HALF TO ROBERT C. CARTER AND GEORGE S. JAMISON, BOTH OF GLENS FALLS, NEW YORK.

WELDING-TORCH BURNER.

Application filed October 16, 1923, Serial No. 668,833. Renewed May 25, 1927.

This invention relates to an improved welding torch burner and seeks, among other objects, to provide a device of this character wherein the gas and air will be caused to flow into the draft tube of the device at a high velocity for preventing back firing of the burner at low gas pressure.

The invention seeks, as a further object, to provide a burner employing a draft tube 10 inside of the mixing chamber of the burner whereby to effect compactness.

A still further object of the invention is to provide a burner which may be readily disassembled for removal of the gas generating tubes of the device, which may be readily cleaned, and wherein freezing of the cleanout plugs or other joints between parts will be obviated.

And the invention seeks, as a still further object, to provide a burner embodying a burner hood constructed to support a kettle, thus adapting the device for use as a fire pot burner as well as a torch, and wherein means will be provided for sustaining the burner under the weight of a kettle.

Other and incidental objects will appear hereinafter.

In the drawings:

Figure 1 is a side elevation showing my improved burner in connection with a torch tank,

Figure 2 is a detail top plan view of the burner,

Figure 3 is a longitudinal sectional view 35 taken on the line 3—3 of Figure 2, looking in the direction of the arrows,

Figure 4 is a transverse sectional view on the line 4—4 of Figure 2, looking in the direction of the arrows,

Figure 5 is a detail sectional view on the line 5—5 of Figure 3, looking in the direction of the arrows, and

Figure 6 is a fragmentary perspective view showing the foot of the supporting 45 leg of the burner.

In carrying the invention into effect, I employ a mixing chamber 10, the end portions of which are cylindrical, while throughout the major portion of its length 50 said chamber is open at its upper side and is, as shown in detail in Figure 5, provided with parallel side walls on which are formed inturned flanges 11. Closing the chamber at its upper side is an apertured burner plate

12 resting flat upon said flanges and detachably securing the plate in position are screws or other suitable fastening devices 13 so that, as will be seen, the burner plate may be readily renewed when necessary. Screwed upon the inner end of the mixing chamber 60 is a cap 14 carrying a ring 15 supported in spaced relation to the cap by a spider 16 and mounted upon said ring is an upstanding valve casing 17 having an axial passage 18 opening at its lower end into a valve chamber 19. At its forward end, said chamber is screwed into the ring 15 and is provided with an end wall 20 in which is formed a central tapered valve opening 21. At its outer end, the chamber is provided 70 with a nipple 22 into which is screwed a needle valve 23 having a reduced portion 24 terminating in a needle point to fit the opening 21. Screwed upon the nipple 22 to surround the valve is a gland 25. Thus, as will be seen, the valve may be adjusted for regulating the flow of fuel gas through the opening 21 of the chamber and screwed through the cap in concentric relation to said opening is a draft tube 26 extending axially of the mixing chamber 10 to a point near its forward end. As brought out in Figure 3, the bore of said tube is gradually reduced from the ends thereof to a point medially of the tube to define a Venturi throat 27. 80 Formed on the valve casing 17 at its upper end is an upstanding bonnet 28 through which is threaded a clamp screw 29 extending axially of the bore 18 of said casing and overlying said bore at its outer end is a closure plate 30 which is preferably constructed of copper and is held by said screw, the screw being rounded at its inner end so as to press the plate slightly into the bore to provide a sealed joint between the plate and the casing. Thus, the bore of the valve casing will be effectually closed while, by removing the plate and clamp screw, a wire or other cleaning device may be inserted 90 through the bonnet into the bore for cleaning the bore. At the same time, freezing of the clamp screw, such as would occur were the screw threaded directly into the bore to form a clean-out plug, will be avoided. Formed on the forward side of the valve casing near the upper end thereof is an annular flange 31 and screwed into the casing concentrically of said flange to com-

minate with the bore 18 is a nipple 32 cooperating with the flange to define a socket 33 in which is disposed a packing 34 which is preferably formed of asbestos.

5 Associated with the mixing chamber is a gas generating unit comprising parallel generating tubes 35 and 36 connected near their forward ends by a cross tube 37. At its rear end, the tube 36 fits snugly in the socket 33 in the valve casing 17 to surround the nipple 32 bearing against the packing 34 and formed on said tube is a flange 38 while the valve casing is provided at its rear side with ears 39 through which are engaged 10 clamping rods 40 screwed through the flange 38 so that, as will be seen, the rods may be adjusted for drawing the tube into the socket to compress the packing and form a tight joint between the tube and casing.

15 Formed on the forward ends of the tubes 35 and 36 are bonnets 41 while the tube 37 is provided at one end with a similar bonnet 42, and screwed through said bonnets are clamp screws 43, these bonnets and clamp 20 screws being similar to the bonnet 28 and clamp screw 29. Secured by said screws over the adjacent ends of the tubes are closure plates 44 which are preferably constructed of copper, the screws being rounded 25 at their inner ends, like the screw 29, for pressing the plates slightly into the adjacent ends of the tubes to form sealed joints between the plates and the tubes. Accordingly, the tubes will be effectually sealed 30 while, by removing the screws 43 and plates 44, the tubes may be readily cleaned. Furthermore, by employing the bonnets and mounting the clamp screws upon the bonnets, the inherent freezing trouble as experienced 35 with clean-out plugs, will be avoided. Formed on the tube 37 at its lower side is a depending plate 45 apertured to fit over the forward end of the mixing chamber 10, supporting the forward ends of the generating 40 tubes 35 and 36 with respect to said chamber, and formed on the lower end of the plate is a rearwardly directed priming pan 46 extending beneath the mixing chamber 10 and valve chamber 19 in close proximity thereto. At its forward end the pan is provided with a depending lug 47 upon which is swingingly mounted a supporting leg 48 connected with the lug by a clamping bolt 49 and formed on the leg at its lower 45 end, is, as shown in detail in Figure 6, an arched foot 50. As suggested in dotted lines in Figure 1, the leg may be disposed in inactive position to extend horizontally beneath the pan 46 when by tightening the bolt 49, the leg will be held in such position.

50 Attention is now directed to the fact that the gas generating unit is freely detachable from the mixing chamber 10 and valve casing 17. By removing the clamping rods

40, the unit may be readily slipped forwardly and displaced. Consequently, the generating unit may be easily renewed at any time should the efficiency thereof be impaired.

70 Removably resting at its ends upon the tubes 35 and 36 of the generating unit is an oblong hood 51 which, as shown in detail in Figure 4, is provided with elongated sides 52 extending downwardly at opposite sides 75 of the mixing chamber 10 and bent inwardly at their lower margins to approach the side walls of the pan 46. Thus, the hood will tend to prevent accidental blowing out of the flame of the burner and rising from the hood at the corners thereof are outwardly inclined rests 53 for supporting a kettle, as conventionally illustrated in Figure 1 at 54. In Figure 1 of the drawings, I have shown the present burner in connection with a 80 torch tank 55, as set forth in my co-pending application for said invention filed May 15, 1923, Serial No. 639,173. It is, accordingly, unnecessary to go into the details of the tank herein, it being sufficient to note that the tank is provided with an outlet pipe 56 through which liquid fuel is delivered under pressure. Connecting the generating tube 35 of the burner with the pipe 56 of the tank is a pipe 57 in which is interposed 90 a swivel joint 58 so that the burner may be swung horizontally, while a similar swivel joint 59 is interposed in the pipe 56 so that the burner may be swung in a vertical plane. Thus, as will be seen, the burner may be disposed over the tank or may be brought to the position shown, when the leg 48 may be swung downwardly for supporting the burner under the weight of the kettle 54. Accordingly, the assembled burner and tank 100 may be readily employed as a fire pot as well as a blow torch.

100 In operation, fuel is poured into the pan 46 and lighted for heating the mixing chamber 10 and valve casing 17 as well as the generating tubes 35, 36 and 37. The needle valve 23 is then opened to permit a flow of fuel through the generating tubes. As the fuel progresses through these tubes, the fuel will, of course, be gasified to issue in vaporous form through the valve opening 20 into the draft tube 26 of the mixing chamber. Air will accordingly be drawn in at the rear end of said tube so that the air and fuel vapors will pass through the tube to be mingled therein and issue into the chamber 10 to be finally mixed and thoroughly mingled within said chamber. From the chamber 10, the fuel mixture will, of course, rise through the openings of the burner plate 12 to be ignited, when the flame will, of course, serve to heat the generating tubes 35, 36 and 37 to maintain the burner in operation. In connection with the draft tube 26, it is to be particularly noted that since 130

this tube is formed with the throat 27, the velocity of the currents of fuel vapor and air going through the tube will be materially increased at said throat. Accordingly, a pressure will be maintained in the mixing chamber 10 sufficiently high to prevent back firing through the burner plate and mixing chamber into the tube when the flow of gas into the draft tube is reduced for reducing the 10 flame at the burner plate.

Having thus described the invention, what is claimed as new is:

1. A burner including a mixing chamber, a cap closing the chamber at one end and 15 provided with a spider having a ring thereon in spaced relation to the cap, a draft tube mounted upon the cap to extend within said chamber and having one end exposed to the atmosphere, and a valve mounted upon said 20 ring for injecting fuel into said tube.

2. In a burner, the combination of a burner unit including a mixing chamber and a valve rigidly connected with said chamber and controlling the flow of fuel thereto, a 25 gas generating unit including a superheater tube having a depending plate apertured to receive the forward end of said chamber and provided with a priming pan extending rearwardly beneath said chamber, the tube

and valve having sliding connection and 30 clamping means binding the tube and valve together and freely releasable whereby the units may be readily separated.

3. A burner including a mixing chamber, a fuel valve controlling flow of fuel into said 35 chamber, and provided with a socket, a gas generating tube fitting in said socket, a nipple fixed to the valve to project within said socket and fitting in the adjacent end of said tube, a packing surrounding the nipple and 40 forming a seat for the end of the tube, and means coating between the tube and valve clamping the tube and valve together to form a sealed connection between the tube and valve. 45

4. In a burner, the combination of a burner unit including a mixing chamber and a valve rigidly connected with said chamber and controlling the flow of fuel thereto, a gas generating unit including a superheater 50 tube having a depending plate apertured to receive the forward end of said chamber, the tube and valve having sliding connection, and clamping means binding the tube and valve together and freely releasable 55 whereby the units may be readily separated.

In testimony whereof I affix my signature.
CHARLES E. CHAPMAN.
